MOUNTING FRAME FOR ELECTRONIC CIRCUITS

Morris H. Brogden, 1416 Lebanon Road, Nashville, Tenn.

Filed June 2, 1959, Ser. No. 56,183

Term of patent 14 years

(Cl. D26—1)

Fig. 1

Fig. 2

Fig. 3

Fig. 4

Fig. 1 is a perspective view of a mounting frame for electronic circuits, showing my new design;

Fig. 2 is an opposite perspective view;

Fig. 3 is a fragmentary side elevational view to an enlarged scale; and

Fig. 4 is a section taken along the line 4—4 of Fig. 1.

This application is a continuation-in-part of my application Ser. No. 50,700, filed May 1, 1958, now abandoned.

I claim:

The ornamental design for a mounting frame for electronic circuits, as shown.
